UNITED STATES PATENT OFFICE.

LAZARD KAHN, OF HAMILTON, OHIO.

STOVE.

No. 859,299.

Specification of Letters Patent.

Patented July 9, 1907.

Application filed May 20, 1904. Serial No. 208,794.

To all whom it may concern:

Be it known that I, LAZARD KAHN, a citizen of the United States, residing at Hamilton, Butler county, Ohio, have invented a new and useful Improvement 5 in Stoves, of which the following is a specification.

My invention relates to stoves of the class used for heating purposes, and the objects of my improvement are to provide the stove body with brackets which are adapted to engage with and support it on the base 10 portion; which serve to support and protect the stove bottom from injury, and which serve also to support the foot rail, the grate and the fire linings.

These objects are attained in the following described manner as illustrated in the accompanying drawings, 15 in which:—

Figure 1, is a side elevation of the stove; Fig. 2, a vertical section of a bracket and parts of contiguous members of the stove; Fig. 3, an isometrical view of a bracket with portions of the base and the foot rail; 20 Figs. 4, 5, 6 and 7, show parts of different forms of base portions.

In the drawings, the stove body 11 preferably consisting of sheet metal and preferably cylindrical in shape is formed with a series of perforations or openings 12 through the lower portion of its side and in a plane parallel with its bottom 13. It is provided with ash pit door and frame 14 and 15, foot rail 16 and the usual top 17. Said top contains flue opening 18, a fuel door (not shown) and is surmounted by a perforated hood 19 which is swiveled thereon in the usual manner.

Brackets or castings 21, are secured to the stove body by means of bolts 22, and toes or tenons 23, preferably flaring in shape, are extended at right angles 35 therfrom under the bottom 13 to which they are secured by means of bolts 24 to strengthen and protect it from injury. Heels 25 terminate the lower end of the brackets below shoulders 26 formed thereon and the toes 23, to form supports for the body on the floor 40 when dismounted from the base, as for shipping or storing. Arms 27 are extended from brackets 21 through openings 12 and terminate within the stove body in offsets or seats 28 wherein grate 29 is movably supported. Said arms are formed with notches 31 to 45 maintain fire linings 32 supported thereon concentric with the grate. Catches 33 formed on the brackets terminate near lugs 34 thereunder to form open angular slots 35, and foot rail 16 is formed with inwardly projecting arms 36 which terminate in upturned extremities 37 adapted to detachably engage with the slots and support the foot rail on the brackets.

The base portion may be plain as shown in Fig. 5, or, as shown in Fig. 4, it may consist of a continuous skirting 41 with legs 42; or with skirting formed in

sections 43 and bolted together as at 44; or with the 55 skirtings in section 45 and bolted to the leg portion 42 of the base; or the leg 42 without any skirting may be formed with inwardly projecting wings 46 having tapering slots 47 between them which are adapted to detachably engage with tenons 23 under bottom 13 60 like an ordinary dove tail.

The base portions are all formed with notches or seats 47 in their upper margin and preferably over the legs 42. Said notches are adapted to detachably engage with the heels 25 of the brackets to maintain the stove 65 body in proper position on the base when it is supported thereon by means of shoulders 26 as shown in Figs. 1 and 2.

Having fully described my improvement, what I claim as my invention and desire to secure by Letters 70 Patent of the United States is:—

1. In a stove, the combination of a stove body provided with a bottom, an independent base portion provided with a seat in its upper edge, a bracket adapted to detachably engage with said seat, and to removably support the stove 75 body on the base portion, and means for securing said bracket to the stove body.

2. The combination of a stove body provided with a bottom, a bracket secured thereto and provided with a heel, said heel depending below the bottom of said body, an independent base portion provided with a seat adapted to engage with said heel and to removably support said bracket together with the stove body thereon. 80

3. The combination of a stove body provided with a bottom, a base independent thereof and provided with seats, 85 brackets provided with heels adapted to detachably engage with the seats and to removably support the stove body on the base, and means for securing the brackets to the stove body.

4. The combination of a stove body, a foot rail, brackets provided with toes adapted to support said body, said brackets being also provided with catches adapted to detachably engage with and support the foot rail, means for securing the brackets to said stove body, and a base constructed to support said brackets. 90

5. The combination of a stove body provided with a plural number of openings in the side thereof, brackets provided with arms adapted to pass through said openings, said brackets being also provided with toes adapted to support the stove body, means for securing said brackets to the stove body, and a base provided with legs and constructed to support said brackets. 95

6. The combination of a stove body provided with a plural number of openings in the side thereof, brackets provided with arms adapted to pass through said openings, 105 said brackets being also provided with means adapted to detachably engage with and support a foot rail, means for securing the brackets to the stove body, and a base constructed to support the brackets.

7. The combination of a stove body provided with a plurality of openings in the side thereof, brackets provided with arms adapted to pass through said openings, said brackets being also provided with toes adapted to support said stove body, and with heels, means for securing said brackets to the stove body, and a base constructed to detachably engage with the heels and support said brackets. 110 115

8. The combination of a stove body provided with a series of openings in the side thereof, brackets formed with arms adapted to extend through said openings, said brackets being also formed with heels, means for securing 5 said brackets to said stove body, and a base constructed to support said brackets and provided with seats adapted to detachably engage with said heels.

9. The combination of a stove body provided with a plurality of openings in its side, brackets formed with

arms adapted to extend through said openings, said 10 brackets being formed with means adapted to support a foot rail, and also with toes adapted to support said stove body, means for securing said brackets to said body, and base portions constructed to support said brackets.
